UNITED STATES PATENT OFFICE

143,987

DESIGN FOR A DENTAL OCCLUSION APPARATUS

Edwin O'Donnell, Alhambra, Calif.

Application March 5, 1945, Serial No. 118,273

Term of patent 3½ years

(Cl. D24—1)

To all whom it may concern:

Be it known that I, Edwin O'Donnell, a citizen of the United States, residing at Alhambra, in the county of Los Angeles and State of California, have invented a new, original, and ornamental Design for a Dental Occlusion Apparatus, of which the following is a specification, reference being had to the accompanying drawings, forming a part thereof.

Figure 1 is a perspective view of a dental occlusion apparatus, showing my new design.

Figure 2 is a top plan view thereof.

Figure 3 is a side elevational view thereof.

Figure 4 is an end elevational view taken from the left of Figure 3.

I claim:

The ornamental design for a dental occlusion apparatus, substantially as shown.

EDWIN O'DONNELL.
